APPARATUS FOR AND METHOD OF IMPREGNATING FELT

Filed Feb. 7, 1925

Patented June 15, 1926.

1,588,748

UNITED STATES PATENT OFFICE.

HENRY C. KOCH, OF CHICAGO, ILLINOIS.

APPARATUS FOR AND METHOD OF IMPREGNATING FELT.

Application filed February 7, 1925. Serial No. 7,502.

My invention relates to apparatus for and method of impregnating roofing and similar material, and the object is to provide apparatus which will occupy a small compass and will quickly and thoroughly saturate or impregnate the felt or other fabric with asphalt or other waterproofing substance with which it is to be combined. A method commonly employed heretofore was to pass a strip of the felt alternately over and under a considerable number of rollers which would cause the felt to pass alternately into and out of a bath of the liquid, but this method is slow and the apparatus occupies a large space in order to provide proper room for the battery of rollers. My purpose is to forcibly combine the liquid with the fabric, especially by means of a vacuum. In a copending application filed January 20, 1925, Serial No. 982, I have shown apparatus for the same purpose in which means are provided for directing jets of the liquid forcibly toward the fabric to thereby cause the liquid to penetrate into its pores. In 25 my present apparatus I provide vacuum means for drawing the liquid into the body of the fabric by suction.

I carry out the principles of my invention by means of apparatus, one form of which 30 is shown in the accompanying drawings in which—

Figure 1 is a general side elevation of the apparatus partly in section.

Figure 2 is an end elevation partly in 35 section on the line 2—2 Figure 1.

Figure 3 is a fragmentary perspective showing a portion of the foraminated vacuum element which supports the fabric as the latter travels past it.

Like numerals denote like parts throughout the several views.

Referring to the drawings, the felt or other fabric to be treated occurs in the form of a strip 1 which is wound upon a storage roll 2 or other convenient means by which the fabric may be fed to the remainder of the apparatus. The substance with which the fabric is to be impregnated is contained within a tank 4. In moving towards the tank 40 the strip passes first over a guide roller 6 mounted at the top of the tank. It passes thence to a second guide roller 8 also located near the top of the tank. The first roller is not essential and may be omitted if desired.

From the roller 8 the strip passes down

and under a roller 10 located near the bottom of the tank. From this the strip passes up over a guide roller 12 which is located at the top of the tank usually not far from the roller 8. From roller 12 the strip passes out of the apparatus. A pressure roller 14 is located above the roller 12, its function being to remove the surplus liquid and permit it to flow back into the tank and also to exert pressure upon the impregnated strip to cooperate with the roller 12 and between them to compact and consolidate the strip and its impregnating substance. It will be understood that means are provided for causing the strip to travel through the apparatus but as means for this purpose are known it is not necessary to show or describe them here.

In producing roofing, the impregnated substance is commonly asphalt or the like which is more or less solid at ordinary room temperature. It is therefore common to provide means for heating the tank to render the contents liquid prior to the commencement of the run; but as the heating may be accomplished in various ways and means for the purpose which are well known I have omitted them from the drawings.

Located within the tank are two vacuum elements 16. These are elongated hollow members which in the form illustrated are rectangular, both in vertical and horizontal cross section. One side wall 18 of each is foraminated and they are located one above the other in the tank and offset in such manner that the external surface of one of the foraminated walls lies approximately in the same vertical plane as the external surface of the foraminated wall of the other unit. It is desirable to additionally offset the vacuum elements to provide for the thickness of the fabric, although the arrangement may be somewhat varied without departing from the spirit of the invention. These vacuum units are so located with respect to the guide roller 8 that the strip passes down from it and thence first across the foraminated face of one of the units and then across the foraminated face of the other.

Leading from the top of each vacuum element 16 are pipes 20 which may occur in the form of various branches as indicated, these branches finally uniting in a duct 22 which leads to the intake of centrifugal pump 24 located above the apparatus as il-

lustrated in Figures 1 and 2. This pump is driven by an electric motor 26 or other suitable type of power mechanism.

A pipe 28 leads from the discharge of the pump down into the tank where it connects with a supply pipe 30 leading from a suitable source of supply of the liquid. A valve 32 controlled by a float 34 regulates the level of the liquid in the tank. Any suitable means, not shown, are employed for heating the liquid as it enters the apparatus through the pipe 30 and in order that the contents of the tank may be kept agitated and the heat more or less uniformly distributed throughout the body of the liquid it is desirable to have the discharge pipe 28 connect with the supply pipe 30 near the discharge mouth of the latter. By this arrangement as the liquid is forced from the pump it merges with the hot liquid entering from the supply pipe and the two streams entering together under pressure tend to agitate the liquid and keep it at uniform temperature.

In operation, after the impregnating substance has been warmed sufficiently to become liquid the pump 24 is started and the strip of fabric is started through the apparatus. As the strip passes down across the foraminated face of the upper vacuum element 16 it closes off the apertures and the result is that the pump in its effort to draw the liquid up through the pipe 20, 22 creates a partial vacuum within the vacuum element, and as the strip is more or less porous a certain amount of the liquid is drawn into the body of the strip, depending upon the degree of porosity of the strip, the viscosity of the liquid and the amount of vacuum within the unit. From the upper vacuum unit the strip then passes to the lower one where the direction is reversed and the liquid is drawn into the body of the strip from the opposite side. Thus both surfaces of the strip are acted upon and penetrated by the liquid, after which the strip passes out of the machine.

As a result of the operation of this apparatus a heavy percentage of liquid is introduced into the body of the strip in a very short period of time and by a machine which is very compact compared to the type of apparatus in which no force is employed for combining the liquid and the fabric and the strip needs to pass around a large number of guide rollers.

It will be observed that my apparatus is simple in construction and that there are no moving parts except the guide rollers and pump. Thus the apparatus is not likely to get out of order.

Having thus described my invention what I claim as new and desire to secure by Letters Patent is:

1. Apparatus for impregnating felt and the like having a tank for the liquid, means for passing a strip of the fabric down into the tank and up out of it, a vacuum element located within the tank, and having a foraminated surface across which the fabric travels, and means for creating suction on the inside of the vacuum element, the vacuum element being stationary and the strip passing across it whereby the strip is subjected both to a rubbing and a sucking action while submerged.

2. Apparatus for impregnating fabric including a liquid bath, means for passing the strip of the fabric through the bath, a hollow vacuum element immersed within the bath, said vacuum element having a foraminated surface across which the fabric travels, and a suction pump connected to the inside of the vacuum element for drawing from it the contents thereof, the vacuum element being stationary and the strip passing across it whereby the strip is subjected both to a rubbing and a sucking action while submerged.

3. Apparatus for impregnating fabric including a liquid bath, means for passing a strip of the fabric through the bath, a vacuum element immersed within the bath, said vacuum element having an apertured surface across which the fabric travels, a suction pump connected to the inside of the vacuum element for drawing from it the contents thereof, and a discharge duct leading from said pump back to the bath whereby continuous circulation is effected, the vacuum element being stationary and the strip passing across it whereby the strip is subjected both to a rubbing and a sucking action while submerged.

4. Apparatus for impregnating felt and the like, having a tank for the liquid, a vacuum element located in the tank below the liquid level and having its acting surface foraminated, a second vacuum element also having a foraminated acting surface and being located in the tank beyond the first one whereby the strip passes across the vacuum element successively, and means for guiding the strip across the acting faces of the vacuum units successively, the acting units being located on opposite sides of the strip, whereby the suction is first in one direction through the strip and then in the opposite direction.

In witness whereof, I have hereunto subscribed my name.

HENRY C. KOCH.
